UNITED STATES PATENT OFFICE.

CHARLES H. BENTON, OF CLEVELAND, OHIO, ASSIGNOR TO OTIS B. BENTON,
OF SAME PLACE.

PANTALOONS-STRETCHER.

SPECIFICATION forming part of Letters Patent No. 352,106, dated November 2, 1886.

Application filed January 16, 1886. Serial No. 188,751. (No model.)

To all whom it may concern:

Be it known that I, CHARLES H. BENTON, of Cleveland, in the county of Cuyahoga and State of Ohio, have invented certain new and useful Improvements in Stretchers for Pantaloons; and I do hereby declare the following to be a full, clear, and exact description of the invention, such as will enable others skilled in the art to which it pertains to make and use the same.

My invention relates to stretchers for pantaloons in which a foot-plate for depressing the lower clamp and stretching the garment and a retaining-pawl for holding the garment taut are employed, the object being to provide a device that is more effective in stretching the pantaloons and is more quickly and conveniently operated than the devices heretofore in use for such purposes.

In the accompanying drawings, Figure 1 is a side elevation of a pantaloons-stretcher embodying my invention. Fig. 2 is a bottom plan of the top clamp. Fig. 3 is a bottom plan of the lower clamp. Fig. 4 is a view in perspective showing the manner of operating the stretcher. Figs. 5 and 6 are details hereinafter described.

Clamps A and B are mounted on the bar C, the former for clamping the pantaloons at or near the waistband, and the latter for clamping the pantaloons near the bottom thereof. These clamps are of similar construction, and are hinged together at one end, and are pressed together at the other end by means of thumb-screws b. The clamp A is attached to the bar C by means of the thimble a, or other suitable device, so that the clamp may be removed from the bar for convenience in packing. The bottom clamp, B, is mounted on the bar C, the latter passing loosely through a guide-block, D, that is secured to this clamp. The bar C may be made in two or more pieces joined by bands c. The lower portion of the bar C has attached a ratchet-plate, c', and the lower clamp has connected therewith a spring-pawl, d, for engaging the teeth of the ratchet-bar and holding the clamp D depressed. A foot-plate, d', is provided for depressing the lower clamp, the operator throwing more or less of his weight thereon as may be needed to stretch the pants.

In operating the device the pantaloons are folded lengthwise and the upper part secured in the clamp A. The legs, near the bottom,

in like manner are secured to the clamp B. 55 The stretcher is held upright, with the lower end of the bar C resting on the floor. The operator places his foot on the foot-plate and depresses the lower clamp to stretch the garment. The dog, engaging the notches of the 60 ratchet, holds the clamp depressed.

The stretching of the pantaloons takes out the bagging at the knees, so that they may be worn a long time and still have a neat and new appearance. When pantaloons are only 65 worn occasionally, they should be left in the stretcher.

For pantaloons that are being worn daily, they should be placed in the stretcher overnight. There is no great strain required, not 70 enough to injure the garment in the least.

Bagging at the knees is caused partly by the cloth stretching at this part and partly by the shrinking or fulling up of the cloth on the opposite side of the pantaloons leg. The 75 stretching reverses the order, straining the rear portion and giving the front portion of the garment an opportunity to shrink or full up, so that when the pantaloons come out of the stretcher they are substantially in the form 80 that they were when new.

Heretofore screw-rods have been employed for operating pantaloons-stretchers; but they were extremely slow and tedious of manipulation.

My improved pantaloons-stretcher is operated easily and quickly, and is therefore especially adapted to the use of tailors, clothiers, and those that repair clothing.

The form of the clamps is not essential, 90 and I do not wish to be understood as limiting myself to the clamp shown.

What I claim is—

In a pantaloons-stretcher, a connecting bar or rod, in combination with two clamps, one secured rigidly to the bar at one end and the other mounted loosely thereon at the other end, pawl-and-ratchet mechanism for adjusting and holding the loose clamps on the bar, and a foot-rest on said clamp to depress it in 100 stretching the trousers, substantially as set forth.

In testimony whereof I sign this specification, in the presence of two witnesses, this 5th day of January, 1886.

Witnesses: CHARLES H. BENTON.

CHAS. H. DORER,

A. E. LYNCH.
